UNITED STATES PATENT OFFICE.

LOUIS H. SOLON, OF CEDAR RAPIDS, IOWA.

TAMPING DEVICE FOR BLOCK-MOLDS.

1,165,809.

Specification of Letters Patent. Patented Dec. 28, 1915.

Application filed June 10, 1914. Serial No. 844,212.

To all whom it may concern:

Be it known that I, LOUIS H. SOLON, a citizen of the United States, residing at Cedar Rapids, in the county of Linn and

5 State of Iowa, have invented certain new and useful Improvements in Tamping Devices for Block-Molds, of which the following is a specification.

This invention relates to tamping devices 10 employed in connection with molds for forming artificial stone building blocks, and its object is to provide a novel and improved fluid-pressure operated tamping device which can be easily controlled, and which is 15 simple in construction and efficient in operation.

This object is attained by means of a combination and arrangement of parts to be hereinafter described and claimed, reference being had to the accompanying drawings, in which—

Figure 1 is an elevation of the device; Fig. 2 is an enlarged vertical section on the line 2—2 of Fig. 1; Fig. 3 is a horizontal 25 section on the line 3—3 of Fig. 1, and Fig. 4 is a sectional detail of a controlling valve.

Referring specifically to the drawings, 10 denotes a mold box constructed and arranged in any suitable or desired manner.

20 Above the mold box is mounted a tamping device comprising a series of tamper feet 11 carried at the lower end of rods 12 attached to reciprocatory plungers 13 working in fluid-pressure cylinders 14. These cylinders are connected at their upper ends to an air-chamber 15, from which they depend in a row. The chamber has an inlet 16 connected to any suitable source of compressed air or other fluid-pressure. The 25 cylinders all open at their upper ends into the chamber and the tampers are therefore operated simultaneously. In the fluid-pressure supply conduit 17 leading to the chamber is a valve 18 provided with an operating handle 19.

40 This valve is so constructed that when the handle is swung to one side, fluid-pressure is let into the chamber to pass into the cylinders, and when the handle is swung to the opposite side, the fluid-pressure 45 sure supply is shut off and at the same time an exhaust port 20 is uncovered to permit escape of the fluid-pressure from the cylinders. The valve handle swings between stops 21, and it is held against either one or 50 the other of said stops by a spring 22 or any

other suitable means. The chamber 15 is mounted in any suitable manner on the ceiling joists or on some other overhead support.

To the lower end of each cylinder 14 is 50 coupled, by means of a reducer 23, a depending tube 24 having a cap 25 fitted to its lower end. The plunger rod 12 passes loosely through this tube and also through a central opening in the cap and depends 55 from the latter. In the tube are side ports 26 to permit the escape of air which is beneath the plunger 13.

Each tamper foot 11 comprises a block having an upstanding top lug 27 fitting 70 against one side of the lower end of the plunger rod 12. Bolts 28 passing through the lug and the plunger rod secure the tamper foot to the latter. The top of the block slopes toward both sides to prevent 75 the material from accumulating thereon. The length of the tamper foot is such that it projects from opposite sides of the plunger rod, and to one of the projecting ends is connected one end of a coiled spring 29 having 80 its other end anchored to any suitable overhead support. This spring is provided for the purpose of retracting the tamper foot.

In operation, air being admitted into the 85 cylinders 14, the plungers 13 are forced downward, and the feet 11 enter the mold box 10 to tamp the material therein. Upon shutting off the air supply and opening the exhaust, the springs 29 elevate the tamper 90 feet and force the plungers back to the upper end of the cylinders for the next stroke, said springs being stretched on the down-stroke. The reducers 23 are encircled by a clamping member 30 to the ends 95 of which latter are connected brace rods 31 extending to the overhead support. The clamping member is in two parts, so that upon removal of one of said parts, any one of the cylinders 14 may be taken down for 100 repairs. The lower ends of the plunger rods 12 are squared or angular in cross-section, and the openings in the caps 25 correspond, whereby the rods and the tamper feet 11 carried thereby, are prevented 105 from turning.

In order to hold any of the tamper feet 11 elevated in inoperative position when making sectional or small blocks, set screws 32 are threaded through the reducers 23. 110

Upon advancing these set screws to bind against the plunger rods 12, the same may be locked in elevated position.

The tamping device hereinbefore described is simple in construction and efficient in operation, and it can be easily controlled. Different sizes of tamper feet may be provided for different sized blocks. The tamper feet are narrow in order that they 10 may pass down between the cores of the mold.

Upon finally tamping the blocks a piece of sheet metal the size of the mold is placed on the block and struck a few times with 15 the tamper-feet, all the tamper-feet being operated simultaneously. If one end of the mold should be filled sooner than the other, both ends will be tamped evenly as the tamper feet work independently of each 20 other.

I claim:

1. A tamping device comprising a fluid-pressure cylinder, a cap mounted on one end of the cylinder and having an angular central opening, a plunger working in the cylinder, side ports in the cylinder near its said end, a rod connected to the plunger and 25

passing through the opening in the cap and projecting therefrom, and a tamper foot carried by the projecting portion of the 30 rod, said portion being angular in cross-section to correspond with the opening in the cap.

2. A tamping device comprising a series of fluid-pressure cylinders, a cap mounted on one end of each cylinder and having an angular central opening, side ports in the cylinder near its said end, a plunger working in each cylinder, a rod connected to the plunger and passing through the opening 40 in the cap and projecting therefrom, a tamper foot carried by the projecting portion of each rod, said portion being angular in cross-section to correspond with the opening in the cap, a two-part clamping member 45 encircling the cylinders and braces connected to said clamping member.

In testimony whereof I affix my signature in presence of two witnesses.

LOUIS H. SOLON.
